[57] ABSTRACT

A gain controlled amplifier circuit in which the amplifying element, such as a transistor, has its emitter-collector circuit connected to a gain control circuit which supplies a constant operating current and changes its AC impedance in accordance with an AGC signal. The gain control circuit includes a first branch having an impedance which varies with the externally applied AGC signal and a second branch having an impedance which varies with the current flow therethrough and which is connected to ground through an AC bypass. These two branches are connected in parallel to a constant current source so that the impedance of the first branch controls the current flow in the second branch and thereby its impedance.

GAIN CONTROLLED AMPLIFIER FOR INTEGRATED CIRCUIT APPLICATIONS

BACKGROUND OF THE INVENTION

1. Field of the Invention

The present invention relates generally to gain controlled amplifier circuits and more particularly to such an amplifier having gain control circuitry which operates in a manner whereby the operational parameters other than gain of the amplifying elements, per se, do not vary with or as the result of the gain control operation.

2. DESCRIPTION OF THE PRIOR ART

In high frequency amplifying circuits, such as are commonly found in RF and IF circuits, some type of gain control is usually found desirable. Typically, some sort of gain control is accomplished in the first stage of the amplifier in order to prevent the successive stages from being overloaded. One of the problems encountered in providing gain control in the first stage of an amplifier, and particularly in integrated circuit amplifier, is that of maintaining the DC voltages (quiescent voltage) applied to the succeeding stages at a constant value so as to maintain the frequency response of the various stages constant as gain control is effected.

The classic method of providing gain control to a transistorized amplifier is to vary the emitter-collector current through one of the input stages. This causes shifts in DC input levels to successive stages which either change their operating point or must be accommodated by appropriate design compromises.

Although there have been a number of techniques recently developed using signal cancellation methods, such techniques are difficult to use because of the symmetric gain control operational characteristics. One technique involves the use of constant emitter degeneration with variable loads and internal transconductance. This method, however, limits the output voltage swing capability and is subject to certain other problems. The difficulties encountered in using such prior art methods have thus made it desirable to seek improved techniques and apparatus for use in gain controlled amplifier circuitry.

OBJECTS OF THE PRESENT INVENTION

It is therefore a primary object of the present invention to provide a novel amplifying circuit having means for providing gain control without changing the operational characteristics of the amplifier stage being controlled.

Another object of the present invention is to provide a novel integrated circuit amplifier having gain control capability which is independent of the operational characteristics of the amplifying stage.

Still another object of the present invention is to provide a novel integrated circuit, gain controlled amplifier using a novel variable AC emitter impedance which varies the gain without changing the operating point of the amplifying stage.

SUMMARY OF THE INVENTION

In accordance with the present invention, a novel gain control circuit is disclosed which provides gain control for transistor amplifiers without affecting the operating characteristics of the amplifier. In a sim-

plified embodiment, the circuit includes a variable impedance transistor branch controlled by a gain control signal and a diode-connected transistor branch. These two branches are connected together in parallel in the emitter circuit of the amplifying transistor which also includes a constant current source, and to ground through an AC bypass. Since the impedance of the diode-connected transistor branch varies with the emitter current flowing therethrough, and since the variable impedance transistor is controlled by the AGC signal, it follows that, since the total emitter current is constant, the current in the diode-connected transistor branch is a function of the impedance of the other branch and controls the AC impedance and therefore the gain of the amplifier circuit.

Also disclosed is an additional embodiment of the invention in the form of a differential amplifier suitable for integrated circuit applications.

The many advantages of the present invention will become apparent to those skilled in the art after having read the following detailed disclosure which makes reference to the several figures of the drawing.

IN THE DRAWING

FIG. 1 is a schematic diagram of an amplifying stage having gain control features provided in accordance with the present invention.

FIG. 2 is a diagram illustrating current vs. gain control voltage at several points in the circuit illustrated in FIG. 1.

FIG. 3 is a diagram illustrating voltage gain vs. gain control voltage in the circuit illustrated in FIG. 1.

FIG. 4 is a schematic diagram illustrating a differential amplifier circuit having gain control features provided in accordance with the present invention.

DETAILED DESCRIPTION OF THE PREFERRED EMBODIMENTS

Referring now to FIG. 1 of the drawing, there is shown in simplified form a one stage transistorized amplifier circuit in accordance with the present invention. The circuit includes an amplifying NPN transistor T_1 having a load resistor R_L coupling its collection 10 to a source of potential V_{cc} , and a gain control circuit 12 coupling its emitter 14 to one side of a constant current source 15. The AC input signals V_{in} to be amplified by the amplifier circuit are applied to an input terminal 16 coupled to the base 17 of transistor T_1 and the amplified AC output signal is taken at an output terminal 18 connected to collector 10.

Gain control circuit 12 includes an externally variable impedance branch having an NPN transistor T_{cs} which has its collector 20 coupled to emitter 14 of transistor T_1 and its emitter 22 coupled to one side of current source 15. Also coupled between emitter 14 of transistor T_1 and current source 15, and in parallel with transistor T_{cs} , is an internally variable impedance branch including a non-linear p-n junction device, such as a diode (not shown) or diode-connected NPN transistor T_d which has its base 24 and collector 26 coupled to each other and to emitter 14, and its emitter 28 coupled to current source 15. A capacitor C_1 is shunted across current source 15 to provide a reference to ground and a low impedance AC path to ground for AC signals. As will be explained hereinafter,

when two stages of this amplifier circuit are combined to form a differential amplifier, a voltage reference is inherently available and no bypass capacitor is necessary.

The AC impedances of current source 15 and of the externally variable impedance branch are made high and of the internally variable impedance branch is made lower so that the AC signals will seek the lower impedance path to ground through the base-emitter junction of transistor T_1 , the device T_d , and capacitor C_1 .

Even though the impedance of transistor T_{cs} is substantially higher than that of diode-connected transistor T_d , and the application of the AGC signal only changes the impedance of transistor T_{cs} slightly, it will still be referred to as a first impedance means since it does change its impedance sufficiently to materially change the current shunted through transistor T_d and thereby control the drain of the amplifier circuit.

The gain control voltage V_{gc} is applied across terminals 27 and 29, i.e., across the base-emitter junction of transistor T_{cs} . Since the emitter current I_e flowing through transistor T_1 is maintained constant because current source 15 is held constant, the current I_d through transistor T_d can be controlled by varying the current I_{cs} through transistor T_{cs} by applying the gain control voltage V_{gc} to the base 30 thereof. And since current I_d determines the effective internal diffusion resistance r_e of transistor T_d to AC signals, as explained in the aforementioned copending application, the AC gain of the amplifying stage can be controlled without changing the operating current I_e through amplifying transistor T_1 .

An analytical approach to the operation of the circuit illustrated in FIG. 1 indicates that an expression for the voltage gain A_v of the circuit can be written as

$$A_v = R_L / (r_e + R_E) \quad (1)$$

where r_e is the internal diffusion resistance of transistor T_1 and R_E is the effective resistance of the gain control circuit 12. Since transistor T_{cs} and T_d are connected in parallel with each other, R_E may be expressed as

$$R_E = (r_o r_d) / (r_o + r_d) \quad (2)$$

where r_o is the dynamic output resistance of transistor T_{cs} and r_d is the internal diffusion resistance of transistor T_d . As mentioned above, r_o is much larger than r_d and can be made essentially an open circuit to AC current. Thus, r_o can be ignored and r_d which can be expressed as

$$r_d = (KT/q) / I_d \quad (3)$$

can be substituted for R_E and equation (1) can be rewritten as

$$(4) \quad A_v = \frac{R_L}{\frac{KT/q}{I_e} + \frac{KT/q}{I_d}}$$

where

K is Boltzmann's constant,
 T is the temperature in degrees Kelvin,
 q is the charge on an electron,

I_e is the emitter current of transistor T_1 , and
 I_d is the emitter current of transistor T_d .
And furthermore, since the current I_e is equal to the sum of the currents I_{cs} and I_d , I_d can be expressed as

$$I_d = p I_e \quad (5)$$

where p is a percentage factor, and accordingly equation (4) can now be rewritten as

$$(6) \quad A_v = \frac{R_L}{\frac{KT}{q I_e} \left(1 + \frac{1}{p} \right)}$$

It will thus be seen that the gain control network 12, while not effecting the emitter current I_e of the amplifying transistor T_1 , does, in response to a gain control voltage V_{gc} , effectively change the AC impedance seen by the emitter 14, and consequently enables the desired gain control function to be accomplished without varying the DC operating current through transistor T_1 .

Among the many advantages of such a circuit technique are that since the operating point of transistor T_1 is maintained constant, the DC output current level at output terminal 18 is maintained constant, the voltage across T_1 is maintained constant, and therefore the frequency response of the transistor can be held constant and be determined quite accurately. Such a circuit, because of V_{be} and resistor matching with the circuitry generating the voltage V_{gc} and the current source I_s , is also accurately reproducible in integrated circuit form.

The operation of the circuit illustrated in FIG. 1 is illustrated by the diagrams shown in FIG. 2 and 3. In FIG. 2 it will be noted that whereas the amplifier operating point current I_e is held constant, an increase in the gain control voltage V_{gc} causes a change in the current I_{cs} through transistor T_{cs} which varies non-linearly in accordance with the operating characteristics of that transistor. And since the diode current I_d through diode-connected transistor T_d is equal to the difference between I_e and I_{cs} , I_d will decrease proportionally as I_{cs} increases.

Referring now again to FIG. 1 of the drawing, it will be appreciated that whereas the proportion of current I_e through T_d is large and thus the value of r_d is small for zero gain control voltage, the current I_d will decrease and therefore r_d will increase as the gain control voltage V_{gc} is increased. Thus, it will be seen that in accordance with the present invention the amplifier gain A_v can be varied between the limits

$$A_v \max = R_L / (2KT/q I_e) \quad (7)$$

and

$$A_v \min = R_L / (KT/q I_e + r_o) \quad (8)$$

Turning now to FIG. 4 of the drawing, a differential amplifier employing the novel gain control technique of the present invention is illustrated and comprises, in essence, two circuits similar to those illustrated in FIG. 1. In this embodiment, the two amplifying NPN transistors T_2 and T_3 have their collectors 40 and 42, respectively, coupled through the load resistors R_2 and R_3 to V_{cc} at terminal 44. The emitters 46 and 48 are

coupled together through a pair of diode connected NPN transistors T_{d2} and T_{d3} , respectively. The input signal v_{in} is applied across the bases 50 and 52 of transistors T_2 and T_3 , respectively, and the resultant output signal v_{out} is taken across the collectors 40 and 42.

The currents through diode connected NPN transistors T_{d2} and T_{d3} are controlled by an input voltage V_{gc} which is applied across the base 54 and commonly connected bases 56 and 58 of the externally variable impedance NPN transistors T_{cs1} , T_{cs2} and T_{cs3} , respectively. The collector 60 of T_{cs1} is coupled to the emitters 62 and 64 of transistors T_{d2} and T_{d3} , respectively, and the emitter 66 is coupled to one side of the current source 67. The collector 68 of transistor T_{cs2} is connected to emitter 46 of transistor T_2 and the collector 70 of transistor T_{cs3} is connected to emitter 48 of transistor T_3 . The emitters 72 and 74 of transistors T_{cs2} and T_{cs3} , respectively, are coupled to the top side of current source 67 along with emitter 66.

In practice, the geometries of transistors T_{cs2} and T_{cs3} are made equal so that their emitter currents I_{cs2} and I_{cs3} are equal. The geometry of transistor T_{cs1} is typically chosen so that the emitter current I_{cs1} is equal to the sum of the emitter currents I_{cs2} and I_{cs3} of transistors T_{cs2} and T_{cs3} , i.e.,

$$I_{cs1} = 2I_{cs2} \quad (9)$$

The operation of the gain control circuitry 80, which includes transistors T_{d2} , T_{d3} , T_{cs1} , T_{cs2} and T_{cs3} , of the differential amplifier embodiment illustrated in FIG. 4 is similar to that of the simplified embodiment illustrated in FIG. 1 in that by controlling the voltage V_{gc} applied to the bases 54, 56 and 58 of transistors T_{cs1} , T_{cs2} and T_{cs3} the current through the diode-connected transistors T_{d2} and T_{d3} can be controlled thereby controlling the impedance seen by the emitters 46 and 48 of the gain of transistors T_2 and T_3 . But whereas an AC low impedance bypass had to be supplied to the single stage embodiment of FIG. 1 in the form of capacitor C_1 , the differential amplifier circuit embodiment of FIG. 4 includes an AC current path. This will become clearer by considering the AC voltage drops in the two circuits. In the circuit of FIG. 1, the AC voltage, at least to a rough approximation, has a drop across the base-emitter junction of transistor T_1 and across diode T_d . As the voltage drop changes, the amplification changes and unless capacitor C_1 were supplied, there would only be a voltage drop across high impedance source 15 and substantially no amplification. In the circuit of FIG. 4, the AC voltage drop of one input voltage with respect to the other is, at least to a rough approximation, across the base-emitter junction of transistor T_2 , across device T_{d2} , across device T_{d3} , and across the emitter-base junction of transistor T_3 . The voltage drops across the amplifying transistors are approximately the same, providing the same gain and the voltage drops across the diode-connected transistor are approximately the same and control the voltage drops across the amplifying transistors and therefore their gain.

As in the previous embodiment, the operation of the circuit of FIG. 4 can also be expressed analytically by noting that with no input signal V_{in} applied to input terminals 51-53

$$I_{e2} = I_{e3} \quad (10)$$

and accordingly

$$I_{e2} = I_{d2} + I_{cs2} \quad (11)$$

Consequently, the voltage gain A_v for the circuit can be written as

$$10 (12) \quad A_v = -\frac{R_L}{KT/q + \frac{r_{o2}r_{d2}}{I_{e2} + r_{o2} + r_{d2}}}$$

15 where r_{o2} is the dynamic output resistance of transistor T_{cs2} and r_{d2} is the internal diffusion resistance of transistor T_{d2} . And as above, since r_{o2} is much greater than r_{d2} , I_{d2} can be written as

$$I_{d2} = pI_s \quad (13)$$

where p is greater than 0, but less than one-half. Thus, equation (12) can be rewritten as

$$14 (14) \quad A_v = -\frac{R_L}{KT/q + \frac{KT/q}{(1/2)I_s + pI_s}}$$

or

$$15 (15) \quad A_v = -\frac{R_L}{KT/q \left(2 + \frac{1}{p} \right)}$$

Thus, when no gain control voltage V_{gc} is applied across 40 terminals 55-57, p will approach one-half and

$$A_{v \max} = -[R_L/(4KT/qI_s)]. \quad (16)$$

45 However, as gain control is introduced by increasing V_{gc} , p will approach zero making the denominator of equation (15) large so that

$$I_{e2} = I_{d2} + I_{cs2} = \frac{1}{2}I_s \quad (17)$$

and thus

$$A_{v \min} = -[R_L/(2KT/qI_s + r_{o2})] \quad (18)$$

55 Therefore, since there is no change in the emitter operating points of either T_2 or T_3 , the small signal bandwidth of the amplifier remains constant independently of gain control and the DC level at output terminals 41-43 also remains constant.

60 It is contemplated that certain modifications of the present invention will become apparent to those of skill in the art after having read the above disclosure. For example, one might choose to modify the circuits to enable the use of PNP transistors instead of the disclosed NPN transistors. An similarly, one might modify the circuit of FIG. 4 for single ended output utilization. Moreover, certain applications may permit the sub-

stitution of field effect transistors for certain ones of the various circuit elements disclosed above. It is therefore, to be understood that the above described circuits are by way of illustration only and are in no way intended to be limiting. Accordingly, I intend that the appended claims be interpreted as covering all modifications which fall within the true spirit and scope of the invention.

What is claimed is:

1. A gain controlled amplifier comprising: 10
an amplifier transistor;
a current source for supplying operating current to
said amplifier transistor; and
gain control circuit means coupling said amplifier
transistor to said current source to couple said
operating current into said amplifier transistor,
said gain control circuit means including 15
a first transistor having an emitter-collector circuit
coupled between said amplifier transistor and said
current source and a base to which a gain control
signal is applied to vary the impedance of said first
transistor, and
a diode coupled in parallel with the emitter-collector
circuit of said first transistor between said ampli- 20
fier transistor and said current source, said oper-
ating current being directed through said diode as
the impedance of said first transistor is changed to
thereby change the impedance of said diode and
the gain of said amplifier transistor.
  2. A gain controlled amplifier as recited in claim 1 30
which further includes means for providing a low im-
pedance AC current path by-passing said current
source.
  3. A gain controlled amplifier as recited in claim 1
wherein said amplifier transistor includes a first elec- 35
trode for receiving an input signal, a second electrode
coupled to said gain control circuit means and a third
electrode from which an output signal can be obtained.
  4. A gain controlled amplifier as recited in claim 1
wherein said amplifier transistor includes a base, an 40
emitter and a collector, and said diode comprises a
transistor having a collector, emitter, and base, the
emitter of said amplifier transistor being coupled to the
base and collector of said diode transistor, and the
diode transistor emitter being coupled to said current 45
5. A gain controlled amplifier as recited in claim 4
wherein the collector of said first transistor is coupled
to the emitter of said amplifier transistor and the
emitter of said first transistor is coupled to the emitter
of said diode transistor.
6. A gain controlled differential amplifier comprising
a first amplifier transistor and a second amplifier
transistor in parallel with said first amplifier
transistor,
a current source for supplying operating current to
said two parallel coupled amplifier transistors,
and a pair of gain control circuit means, one for each
of said amplifier transistors and coupling said as-
sociated amplifier transistor to said current source
to couple operating current into the associated
amplifier transistor, each of said gain control cir-
cuit means including
a first transistor having an emitter-collector circuit
coupled between said associated amplifier
transistor and said current source and a base to
which a gain control signal is applied to vary the
impedance of said first transistor, and
a diode coupled in parallel with the emitter-collec-
tor circuit of said first transistor between said as-
sociated amplifier transistor and said current
source, said operating current being directed
through said diode as the impedance of said as-
sociated first transistor is changed to thereby
change the impedance of said diode and the gain
of said amplifier transistors.
7. A gain controlled differential amplifier as claimed
in claim 6 including an additional transistor with its
emitter-collector circuit coupled between the two
diodes and the current source and having a base to
which said gain control signal is coupled.
8. A gain controlled differential amplifier as recited
in claim 6 wherein said amplifier transistors each in-
clude a base, an emitter and a collector, and said diodes
each comprise a transistor having a collector, emitter,
and base, the emitters of said two amplifier transistors
being coupled to the base and collector of the as-
sociated diode transistor, and the diode transistor emitters
being coupled to said current source means.

source means.
